UNITED STATES PATENT OFFICE.

EDWARD L. TORSCH AND JAMES R. LEE, OF BALTIMORE, MARYLAND.

DESIGN FOR A BADGE-HEADING.

SPECIFICATION forming part of Design No. 23,058, dated February 13, 1894.

Application filed January 12, 1894. Serial No. 496,682. Term of patent 7 years.

To all whom it may concern:

Be it known that we, EDWARD L. TORSCH and JAMES R. LEE, citizens of the United States, residing at Baltimore, State of Maryland, have invented and produced a new and original Design for a Badge-Heading, of which the following is a specification, reference being had to the accompanying drawings, forming a part thereof, in which—

10 Figures 1 and 2 represent respectively, the obverse and an edge view of a badge heading embodying our new design.

15 The leading feature of our design consists in the marginal configuration shown. Thus each side edge is arched or outwardly curved at the center, as at *a*, and from each end of such curved portion extend outward in a direction

toward the end, the straight members *b*, and the members *b* are lapped by the straight members *c* that range parallel with, and within the lines of the members *b*. The longitudinal side edges are completed by the inwardly-curved terminals *d* that join the end edges *e*. The end edges are straight except the center, which is in the form of an ogive. 25

We claim—

The design for a badge heading herein shown and described.

EDWARD L. TORSCH.
JAMES R. LEE.
